UNITED STATES PATENT OFFICE.

CARROLL D. CLIFFELL AND GEORGE MANIKOWSKE, OF WYNDMERE, NORTH DAKOTA.

SWING.

1,335,938.

Specification of Letters Patent. Patented Apr. 6, 1920.

Application filed May 26, 1919. Serial No. 299,823.

To all whom it may concern:

Be it known that we, CARROLL D. CLIFFELL and GEORGE MANIKOWSKE, citizens of the United States, residing at Wyndmere, in the county of Richland and State of North Dakota, have invented certain new and useful Improvements in Swings; and we do hereby declare the following to be a full, clear, and exact description of the invention, such as will enable others skilled in the art to which it appertains to make and use the same.

Our invention relates to improvements in swings of the type having means whereby the occupant may start and propel the same by foot and arm movements.

To the above end, the invention consists of the novel devices and combinations of devices hereinafter described and defined in the claims.

In the accompanying drawings, which illustrate the invention, like characters indicate like parts throughout the several views.

Referring to the drawings:—

Figure 1 is a view in side elevation showing the improved swing in different positions by means of full and broken lines;

Fig. 2 is a front elevation of the swing; and

Fig. 3 is a perspective view of the lower portion of the swing, on an enlarged scale.

The numeral 4 indicates an overhead swing support which, as shown, is in the form of a horizontal beam supported at its ends on a pair of upright posts 5 set in the ground. Bolted or otherwise rigidly secured to the under face of the beam 4, is a head plate 6, having at each end two depending eye-bolts or other suitable supports 7 and 8 spaced, the former in advance of the latter, in respect to the plane of the oscillation of the swing. It is important to note, as shown in Fig. 1, that the supports 7 are located at a higher elevation than the supports 8, for a purpose that will presently appear. While the head plate 6 is shown attached to an overhead beam, it may readily be attached to the horizontal member of a door frame, or the ceiling of a room or porch.

Seat-suspending members or cables 9 have their upper ends secured to the supports 8 and their lower ends are secured in eyes formed in the intermediate upper portions of plates 10, secured to the ends of a seat 11. This seat 11 may take various different

forms and be constructed from any suitable material, such as pressed metal. If desired, the seat 11 may be provided with a back and the height of said seat, from the ground, 60 may be varied, at will, by adjusting the seat-suspending members 9 in the eyes of the seat plates 10.

The upper ends of a pair of pulling members or cables 12 are secured to the supports 65 7, and their lower ends are secured to forwardly offset eye-equipped lugs 13, integrally formed with the upper ends of a pair of tubular handles 14, through which the seat-suspending members 9 loosely extend. Extending in front of the seat 11 and below the same, is a horizontal foot rest 15, in the form of a rod, the ends of which, as shown, are bent to afford a pair of diverging arms 16. These arms 16 project upwardly 70 and rearwardly and have their upper ends integrally formed with the lower ends of the handles 14.

Motion to the swing is set up and maintained as follows:—

The person wishing to swing enters the swing by stepping on the foot rest 15, and, at the same time, grasping the sliding handles 14, and thereafter taking the seat 11, while the swing is in rest position as shown 80 by full lines in Fig. 1. Stepping on the foot rest 15, tends to bring said foot rest, seat 11 and handles 14 into more nearly a straight line, thus assisting the person in taking the seat by bringing said seat closer 85 to the foot rest. When the weight of the operator rests on the seat 11, gravity tends to bring the seat 11, sliding handles 14 and seat-suspending members 9 into substantially the same vertical plane with the supports 8.

Having taken up the above described position, the operator next pulls down slightly on the sliding handles 14, thereby transferring a part of his weight from the seat 11 100 to the pulling members 12, which tends to cause the swing to move forward, as indicated by broken lines in Fig. 1. At the same time that the operator pulls down on the handles 14, it is natural to assist in 105 raising his body by stepping more heavily on the foot rest 15, which results in still further removal of his weight from the seat 11. As the swing comes to rest, at the limit of its forward travel, gravity asserts itself 110 and finally causes the swing to start on its backward course. Gravity is assisted in

this return movement of the swing by the operator throwing his entire weight on the seat 11 and releasing his pull on the sliding handles 14 and foot rest 15. As the swing 5 finally comes to rest, at the limit of its backward movement, the operator again transfers part of his weight from the seat 11 to the handles 14 and foot rest 15, as before described, and again assists gravity in causing the swing to travel forward. It is evident that the repeated action of the person swinging, in the manner just described, will result in the amplitude of the swing being increased to any desired amount and therefore 10 after easily maintained as long as may be desired.

The swinging may be stopped by "letting the old cat die" in the usual manner, so well known among children, or it may be quickly stopped by reversing the process of movements used in setting up the swinging motion.

As previously stated, the supports 8 for the seat-suspending members 9, being at a 25 lower elevation than the supports 7 for the pulling members 12, are very desirable, for the reason that, as the swing reaches its rearmost position, the radii 8 to 14 and 7 to 14 tend to coincide, thus bringing the arcs 30 of travel of the seat 11, handles 14 and foot rest 15 into more nearly concentric circles. This is highly desirable and necessary, for the reason that if the supports 7 and 8 were at the same level, the arcs of oscillation of 35 the seat 11 and foot rest 15 would tend to constantly come nearer together, and the handles 14 to continually rise, thereby pulling the said handles out of the hands of the operator and the foot rest 15 would tend to 40 lift the operator out of the seat 11 at the rearward movement of the swing.

As the swing travels from its rearmost position to its foremost position, the supports 8, being lower than the supports 7, 45 result in the foot rest 15 and the seat 11 separating more and more as the swing approaches its foremost position, thus enabling the person swinging to take the natural 50 straightened-out position, which is customary in the ordinary swing. Further, sup-

ports 8 being lower than supports 7, it is possible to position said supports 7 farther from the supports 8 in a horizontal direction, in respect to the plane of the oscillation of the swing, without unduly pushing 55 the person swinging off the seat 11, at the rearmost position of the swing, or, by reason of the foot rest 15 rising relative to the seat 11. This results in greater ease in starting 60 from a rest position, for it is evident that the farther apart in horizontal directions the supports 7 and 8 are, the easier the starting will be, as will also be the continued swinging.

What we claim is:—

1. A swing comprising an overhead support, a seat, a pair of suspension members suspending the seat from the overhead support, a pair of pulling members attached to the overhead support and offset from the 70 seat suspension members in the plane of oscillation of the swing, a pair of handles slidable on the seat suspension members and attached to the pulling members, and a foot rest having a pair of arms attached to the 75 handles and rigidly connecting the foot rest thereto.

2. A swing comprising an overhead support, a seat, a pair of suspension members suspending the seat from the overhead support, a pair of pulling members attached to the overhead support at a different elevation than the attachment of the seat suspension members therewith, said pulling members being offset from the seat suspension members in the plane of the oscillation of the swing, a pair of handles slidable on the seat suspension members and attached to the pulling members, and a foot rest having a pair of arms attached to the 80 handles and rigidly connecting the foot rest thereto.

In testimony whereof we affix our signatures in presence of two witnesses.

CARROLL D. CLIPFELL.
GEORGE MANIKOWSKE.
